COMBINATION CRIB AND PLAY PEN

Frank L. Odom, Long Beach, Calif.

Application April 14, 1942, Serial No. 438,940

5 Claims.

(Cl. 5—99)

The present invention relates to new and useful improvements in combination cribs and play pens, and has for one of its important objects to provide, in a manner as hereinafter set forth, a device of this character comprising novel means for detachably but firmly securing the parts or members together in either assembled position.

Another very important object of the invention is to provide a combination crib and play pen of the character described which, when disassembled and not in use, will occupy a minimum of space in storage.

Other objects of the invention are to provide a combination crib and play pen of the aforementioned character which will be comparatively simple in construction, strong, durable, light in weight, attractive in appearance, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in end elevation thereof with a corner portion broken away in section.

Figure 2 is a view in vertical longitudinal section through the device assembled as a crib.

Figure 3 is a fragmentary view in vertical section through an upper corner portion of the crib.

Figure 4 is an elevational view, looking at the inside of one of the ends with portions thereof broken away.

Figure 5 is a detail view in side elevation of one of the play pen connections.

Figure 6 is an elevational view of the floor in folded position.

Figure 7 is a perspective view of the device assembled as a play pen.

Figure 8 is a perspective view of the device assembled as a crib.

Referring now to the drawings in detail, it will be seen that the embodiment of the invention which has been illustrated comprises a bottom 1. The bottom 1 includes a pair of substantially rectangular folding frames 2 which are hingedly connected at 3. Mounted on one side of the frames 2 are panels 4 of plywood or other suitable material. Mounted on the other sides of the frames 2 is a suitable bed spring 5. Also mounted on these sides of the frames 2 are substantially triangular corner braces 6 which support the bottom 1 when the device is in use as a play pen. The corner portions of the panels 4 have formed therein openings 7 (see Fig. 1), the purpose of which will be presently set forth.

Mounted on the bottom 1, when the device is being used as a play pen, are duplicate ends and sides 8 and 9, respectively. The ends 8 include

spaced, parallel rails 10 having extending therebetween, at intermediate points, spaced parallel bars 11 and 12. Panels 13 are mounted on the outer sides of the bars 11 and 12 and extend between the rails 10. The ends 8 further include vertical and horizontal rods 14 and triangular braces 15. Mounted for longitudinal sliding movement on the end portions of the rails 10 and adapted to project beyond the ends thereof are hooks 16. The hooks 16 are mounted on the outer sides of the rails 10 and comprise longitudinal slots 17 which accommodate the headed securing screws 18. Countersunk in the inner sides of the rails 10, at points adjacent one end thereof and the bar 12, are keyhole plates 19. The purpose of the members 16 and 19 will be presently set forth. The ends 8 still further include bars 20 extending between one end portion of the rails 10, which bars carry one end of certain of the rods 14.

The sides 9 include upper and lower parallel rails 21 and 22, respectively, having their ends secured to posts 23. The lower end portions of the posts 23 extend below the rails 22 for engagement in the openings 7 in the corner portions of the bottom 1 when the device is used as a play pen. Vertical rods 24 extend between the rails 21 and 22. The sides 9 further include triangular corner braces 25. Mounted in the upper and lower portions of the posts 23 are screws 26, the heads of which protrude from said posts for engagement either in the hooks 16 or the keyhole plates 19.

It is thought that the manner of erecting the device for either of its two uses will be readily apparent from a consideration of the foregoing. Briefly, when the device is to be used as a play pen, the bottom 1 is unfolded on the hinges 3 and placed in a position with the panels 4 uppermost, said bottom resting on the braces 6. The posts 23 of the sides 9 are then inserted in the openings 7 in the bottom 1 where, as illustrated to advantage in Figure 1 of the drawings, they may rest on the braces 6. The ends 8 are then inserted between the end portions of the sides 9 and the hooks 16 are projected and engaged with the headed elements 26. When thus erected, the ends 8 traverse the hinged connection between the sections comprising the bottom 1. When the device is to be used as a crib, the ends 8 are positioned with the rails 10 vertical and the bars 20 uppermost. The bottom 1 is then folded on the hinges 3 with the bed spring 5 outermost and said bottom is placed between the ends 8 with its end portions resting on the bars 12, as seen in Figure 2 of the drawings. When in this position, the ends of the folded bottom 1 abut the panels 13. The sides 9 are then inserted between the ends 8 and the headed elements 26 are engaged in the slots of the keyhole plates 19, thereby firmly but detachably securing

the ends and the sides together with the posts 23 abutting the rails 10.

It is believed that the many advantages of a combination crib and play pen constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A combination crib and play pen comprising a pair of elongated end members, a pair of elongated side members, means for separably connecting the ends of the end members with the ends of the side members to form a rectangular play pen enclosure when the members are all disposed with their major axes horizontal, means for separably connecting the ends of the side members with the upper portions of the sides of the end members to form a rectangular crib frame when the side members are disposed with their major axes horizontal and the end members are disposed with their major axes vertical, a foldable bottom member of a size when open to have the end and side members rest thereon and form a floor for said play pen enclosure, means to prevent lateral displacement of the enclosure relative to said floor, said bottom being of a size when folded to fit in and form a bottom for the crib frame, and means to removably support the folded bottom member in the crib frame above the lower ends of said end members and at the bottoms of said side members.

2. A combination crib and play pen comprising a pair of elongated end members, a pair of elongated side members, means for separably connecting the ends of the end members with the ends of the side members to form a rectangular play pen enclosure when the members are all disposed with their major axes horizontal, means for separably connecting the ends of the side members with the upper portions of the sides of the end members to form a rectangular crib frame when the side members are disposed with their major axes horizontal and the end members are disposed with their major axes vertical, a foldable bottom member of a size when open to have the end and side members rest thereon and form a floor for said play pen enclosure, means to prevent lateral displacement of the enclosure relative to said floor, said bottom being of a size when folded to fit in and form a bottom for the crib frame, and means to removably support the folded bottom member in the crib frame above the lower ends of said end members and at the bottoms of said side members, said bottom member having floor panels on one side thereof and further having a bed spring on the other side of the same arranged to be exposed for use when said bottom member is folded.

3. A combination crib and play pen comprising a pair of elongated end members, a pair of elongated side members, means including hooks slidably mounted at the corners of the end members to project beyond the ends thereof for separably connecting the ends of the end members with the ends of the side members to form a rectangular play pen enclosure when the members are all disposed with their major axes horizontal,

means for separably connecting the ends of the side members with the upper portions of the sides of the end members to form a rectangular crib frame when the side members are disposed with their major axes horizontal and the end members are disposed with their major axes vertical, a foldable bottom member of a size when open to have the end and side members rest thereon and form a floor for said enclosure, means to prevent lateral displacement of the enclosure relative to said floor, said bottom being of a size when folded to fit in and form a bottom for the crib frame, and means to removably support the folded bottom member in the crib frame above the lower ends of said end members and at the bottoms of said side members.

4. A combination crib and play pen comprising a pair of elongated end members, a pair of elongated side members, means for separably connecting the ends of the end members with the ends of the side members to form a rectangular play pen enclosure when the members are all disposed with their major axes horizontal, means including keyhole plates carried by the end members at the corners of one end and substantially intermediate the ends of said end members for separably connecting the ends of the side members with the upper portions of the sides of the end members to form a rectangular crib frame when the side members are disposed with their major axes horizontal and the end members are disposed with their major axes vertical, a foldable bottom member of a size when open to have the end and side members rest thereon and form a floor for said enclosure, means to prevent lateral displacement of the enclosure relative to said floor, said bottom being of a size when folded to fit in and form a bottom for the crib frame, and means to removably support the folded bottom member in the crib frame above the lower ends of said end members and at the bottoms of said side members.

5. A combination crib and play pen comprising a pair of elongated end members, a pair of elongated side members, means for separably connecting the ends of the end members with the ends of the side members to form a rectangular play pen enclosure when the members are all disposed with their major axes horizontal, means for separably connecting the ends of the side members with the upper portions of the sides of the end members to form a rectangular crib frame when the side members are disposed with their major axes horizontal and the end members are disposed with their major axes vertical, a foldable bottom member of a size when open to have the end and side members rest thereon and form a floor for said play pen enclosure, means to prevent lateral displacement of the enclosure relative to said floor, said bottom being of a size when folded to fit in and form a bottom for the crib frame, and means to removably support the folded bottom member in the crib frame above the lower ends of said end members and at the bottoms of said side members, said last-named means comprising transverse bars substantially intermediate the ends of said end members, and a panel extending transversely of the end members in position to be abutted by the folded bottom member when disposed on said transverse bars.

FRANK L. ODOM.
